Inventor:
H. A. L. Kirk
Per Minuflo
Attorney

United States Patent Office.

WILLIAM A. L. KIRK, OF HAMILTON, OHIO.

Letters Patent No. 74,381, dated February 11, 1868.

IMPROVEMENT IN WORKMEN'S TIME-REGISTER.

The Schedule referred to in these Letters Patent and making part of the same.

TO ALL WHOM IT MAY CONCERN:

Be it known that I, WILLIAM A. L. KIRK, of Hamilton, in the county of Butler, and State of Ohio, have invented a new and useful Improvement in Workman's Time-Register; and I do hereby declare that the following is a full, clear, and exact description thereof, which will enable those skilled in the art to make and use the same, reference being had to the accompanying drawings, forming part of this specification, in which—

Figure 1 represents a perspective view of my improved time-register.

Figure 2 represents a plan view of the check-receiver detached.

Figure 3 represents a side view of the same, partly in section.

Figure 4 represents a top view of the register.

Figure 5 is a segmental section through the time-indicator, in the line x x , fig. 1.

Figure 6 represents workmen's checks.

Figure 7 represents plan of keeping time-book.

Similar letters of reference indicate corresponding parts.

This invention relates to an improvement in the construction and arrangement of a time-register, or instrument for recording the working-hours of operatives in a shop or factory, and consists in a deep horizontal cylinder, divided circumferentially into two sections, and each section divided segmentally into twelve compartments or other subdivisions, corresponding to hours or fractions of time.

The cylinder, thus subdivided, is fixed on a vertical spindle attached to a coil spring, which gives it motion when free to move, and is provided with a catch-lever, connected with a clock-movement, that trips the lever from time to time, as desired, to allow the time-box to revolve a certain space, to change the position of the compartments therein, for receiving checks of the workmen as they commence or quit work, to indicate the time, which is registered by a series of figures on the circumference of the cylinder, in the manner hereinafter more minutely described.

A is a round metal box or cylinder, divided vertically into two sets of segmental time-compartments, a a and b b . In the cover, B, of the cylinder are made slots, a' and b' , placed over the compartments a a and b b respectively, for receiving the checks of workmen on passing in or out at the time of their commencing or quitting their work, one set of compartments, a a , thus receiving the checks which indicate the time when a workman commences, and the other set, b b , the checks indicating the time when he quits work. The upper edge of the circumference of the cylinder A is cut into a ratchet with notches c c c , each compartment in the cylinder having three notches opposite, and under the notches are marked figures from number 1 to 12, corresponding with hours of time, which figures indicate the compartments corresponding to them, either for commencing or quitting time, which are under the check-slots a' or b' , as may be set to be indicated there by a pointer, d, in the front of the cylinder. The cylinder A is fixed upon a vertical spindle, C, at the foot of which is attached a coil spring, e, from a catch-lever, g, which is pivoted on the cover B, and connected with a clock placed above the register by means of a wire, shown in red, which lifts the lever to release it at half hours, or other stated times, as may be arranged, to permit the cylinder to move as far around as required to change the position of the compartments a a and b b under the check-slots a' b' . On the lower edge of the circumference of the cylinder A are marked two sets of figures, from 1 to 12, arranged according to a system of combined alternation, by which are indicated the particular compartments in the cylinder A from which the workmen's recording-checks are discharged when the clerk makes the record in a time-book kept for the purpose. One set of figures corresponds to the commencing and the other to the quitting compartments, and each set is provided with a guard or cover, h and k , fitted over the figures, in each of which covers are three ports or openings, m, to expose one figure in the front part of the cylinder whenever the time is recorded by the clerk. These covers h and k serve as bottoms for the compartments in the cylinder A, one for the commencing and the other for the quitting set, and each one may be moved around by hand, independently of the other, for discharging the workmen's time-checks deposited in the compartments. Each of the bottom-covers or guards h k has an opening in it, corresponding to one of the compartments, so that, when either cover is moved around, the workmen's checks in a compartment shall fall

out through the openings, or either of them, which particular compartment from which the checks are thus taken is indicated by one or the other of the port-holes *m*, which exposes the figure corresponding to the time when the check was deposited by the workman in either the commencing or quitting compartment. Springs *s* are attached to the covers *h k*, which catch in cavities *n n* made in the circumference of the cylinder *A*, fig. 5, each notch corresponding to one of the compartments, so that, as the covers are moved around, the springs stop and the compartment is indicated through the port-holes *m*, from which the workmen's checks are discharged, when they fall through the openings in the covers, shown unshaded in fig. 2.

The operation of the register is as follows: The catch-lever *g* having been properly arranged in connection with a clock-movement at thirty minutes past each hour, the lever rises, and the commencing-slot opens for the next hour, while the quitting-slot for the current hour closes. At the expiration of the hour, the lever allows the cylinder to turn to the next stop, which opens the quitting-slot for the hour just expired, but the commencing-slot remains open until it is desirable to have it shut, which may be five, seven, or ten minutes after. The next movement will shut the commencing but allow the quitting-slot to remain open until thirty minutes have elapsed, and then the movement goes on as before.

By these peculiar movements it will be seen that no advantage can be taken by a dishonest workman, which would be the case if the commencing-slot, for example, should open at twelve o'clock, when the quitting-slot opened for that hour, as then the dishonest workman could deposit a check for the commencing hour of one o'clock, and not return to his work until he pleased.

Now, when the workmen's checks have been deposited for commencing and quitting work, and the checks have been discharged, as before described, the clerk records the time in a book, ruled as shown in fig. 7, wherein the day of the month is to be set opposite three columns, running through the days of the week, each day being divided into morning and afternoon, and the time of commencing placed in one column below the time of quitting in another column, the difference noted below showing the time of work actually performed.

Having described my invention, I claim as new, and desire to secure by Letters Patent—

1. The cylinder *A*, divided into two sets of time-compartments, circumferentially and segmentally, as described, rotated by the spring *e* from time to time, and provided with a catch-lever connected with a clock-movement, and working in a ratchet, as and for the purposes specified.

2. The combination of the cylinder *A*, marked with sets of figures corresponding to the hours and to the time-compartments within the cylinder, as described, and the movable covers *h k*, provided with stop-springs *s* and port-holes *m m*, for indicating the time of a workman's commencing and quitting work, as herein shown and set forth.

WM. A. L. KIRK.
